UNITED STATES PATENT OFFICE.

AARON H. WOLFF, OF NEW YORK, N. Y.

DESIGN FOR A GAS HEATER.

60,635.

specification for Design. Patented Mar. 14, 1922.

Application filed September 2, 1921. Serial No. 498,128. Term of patent 14 years.

To all whom it may concern:

Be it known that I, AARON H. WOLFF, a citizen of the United States, residing at the borough of Manhattan, in the city, county, and State of New York, have invented a new, original, and ornamental Design for Gas Heaters, of which the following is a specification, reference being had therein to the accompanying drawings, which form a part thereof.

In the drawings:—

Fig. 1 is a front view of the gas heater, embodying my design;

Fig. 2 is a side view thereof.

As indicated in the drawings, the upper part of the front portion of the heater about the opening for the radiant heating elements is concaved and polished so as to constitute a reflector.

I claim:

The ornamental design for a gas heater, substantially as shown and described.

AARON H. WOLFF.
